UNITED STATES PATENT OFFICE.

CARL E. ANDERSON, OF WORCESTER, MASSACHUSETTS.

DOOR-LATCH.

1,372,000.

Specification of Letters Patent. Patented Mar. 22, 1921.

Application filed July 23, 1919. Serial No. 312,735.

To all whom it may concern:

Be it known that I, CARL E. ANDERSON, a subject of the King of Sweden, residing at Worcester, in the county of Worcester and

5 State of Massachusetts, have invented a new and useful Door-Latch, of which the following is a specification.

This invention relates to a door latch of the general type shown in my prior application, Serial No. 280,298, filed March 3, 10 1919.

It is the object of my present invention to improve the construction of the door latch therein shown in certain respects, and particularly to provide improved devices for manually releasing the bolt, by which a wider range of motion of the handle is permitted.

15 In the preferred form of my invention, a direct gear connection is provided between the releasing handle and the slideable locking member to be described.

A further object of my present invention is to provide a spring directly connected between the pivoted bolt and the said locking member, effective to move the bolt to inoperative position and the locking member to operative position.

Further features of my invention relate to arrangements and combinations of parts hereinafter described and more particularly pointed out in the appended claims.

A preferred form of my invention is shown in the drawings in which—

35 Figure 1 is a plan view of my improved door latch;

Fig. 2 is a side elevation of the door latch, with portions of the casing broken away;

Fig. 3 is a sectional end elevation taken 40 along the line 3—3 in Fig. 1;

Fig. 4 is a view similar to Fig. 3, but showing the parts in a different position, and

45 Fig. 5 is a detail sectional view of the locking member, taken along the line 5—5 in Fig. 3.

Referring to the drawings, my improved door latch comprises a striker 10, commonly secured to a fixed door frame 11, and a casing 12, commonly mounted upon the door 13. A bolt 14 is pivoted at 15 in the casing 12, the bolt being provided with a downwardly projecting arm 16 disposed in the path of the striker 10. A second arm 17 50 of the bolt 14 is positioned behind the

striker 10 as the door is closed, and is securely held in this position by the engagement of a locking member 18 with a third arm 19 of the bolt 14.

The locking member is preferably formed 6 as a box-like structure sliding freely within the casing 12 and is provided with an inclined or wedge-like portion 20 which engages the arm 19. A coil spring 21 is connected at its upper end to the locking member 18 and at its lower end to the arm 17 of the bolt 14. The spring is effective to move the locking member to operative position and the bolt to inoperative position.

When the locking member is raised, as 70 shown in Fig. 3, the bolt will be swung upon its pivot to a position in which the arm 19 thereof stands beneath the end of the wedge-like portion 20 of the locking member. This arrangement of parts holds the 75 locking member in raised position, and also yieldingly retains the bolt in inoperative position.

For the purpose of raising the locking member 18 to release the bolt, I provide said 80 member with a series of rack teeth 22, formed on one edge thereof and projecting through a slot in the casing. These teeth are engaged by a segment gear 23 mounted upon a shaft 24 to which one or more handles 25 may be secured.

I have thus provided a direct gear connection between the handle shaft and the locking member 18, by which said member may be raised to release the bolt. By this 90 connection, a considerable range of movement of the handles 25 is permitted, a feature which is found desirable under certain conditions of use.

It will further appear that the door latch 95 herein described is of exceedingly simple construction, with very few parts and with little possibility of accident or failure of operation.

Having thus described my invention, it 100 will be evident that changes and modifications can be made therein by those skilled in the art within the scope of my invention as set forth in the claims, and I do not wish to be otherwise limited to the details herein 105 disclosed, but what I claim is:—

1. A door latch having, in combination, a striker, a casing, a bolt pivoted therein, a locking member for said bolt movably mounted in said casing and having a plu- 110

rality of teeth formed directly thereon, a segment gear meshing with said teeth, and manual means to actuate said gear to move said locking member to inoperative position.

5 2. A door latch having, in combination, a striker, a casing, a bolt pivoted therein, a locking member for said bolt movably mounted in said casing, a handle, a positive gear connection between said handle 10 and said member, and a yielding connection between said member and said bolt effective to move said member to operative position, and said bolt to inoperative position.

3. A door latch having, in combination, a 15 striker, a casing, a bolt pivoted therein, a locking member for said bolt slidable in said casing said member having rack teeth thereon, a segment gear meshing with said rack teeth, and manual means to actuate said seg-

ment gear to move said locking member to 20 inoperative position.

4. A door latch having, in combination, a striker, a casing, a bolt pivoted therein, a recessed locking member for said bolt of hollow, substantially rectangular construction fitting within said casing and slidable therein, manual means to withdraw said member from locking position, and a spring disposed within the recess of said member and connected at one end to said member and 25 at the other end to said bolt, said spring being effective to move said member to operative position and said bolt to inoperative position.

In testimony whereof I have hereunto 30 affixed my signature.

CARL E. ANDERSON.
